SEWING MACHINE BRACKET ARM

Jan Szostak, Linden, and George D. La Police, Somerville, N.J., assignors to The Singer Company, New York, N.Y., a corporation of New Jersey

Filed Feb. 27, 1969, Ser. No. 15,944

Term of patent 14 years

Int. Cl. D15—09

U.S. Cl. D70—1

Fig. 1

Fig. 2

Fig. 3

Fig. 4

Fig. 5

Fig. 6

FIG. 1 is a front perspective view of a sewing machine bracket arm showing our new design;

FIG. 2 is a front elevational view thereof;

FIG. 3 is a rear elevational view thereof;

FIG. 4 is a top plan view thereof;

FIG. 5 is an end elevational view as seen from the left of FIG. 2;

FIG. 6 is an end elevational view as seen from the right of FIG. 2.

We claim:

The ornamental design for a sewing machine bracket arm, substantially as shown.
